STAFF MOUNTING DEVICE

Barney W. Greenhoe, East Grand Rapids, Mich.

Application April 27, 1934, Serial No. 722,663

3 Claims. (Cl. 248—41)

The present invention relates to mounting devices for flag staffs and the like; and its object is to provide an improved device for detachably mounting such a staff on a horizontal bar.

5 This and any other and more specific objects hereinafter appearing are attained by, and the invention finds preferably embodiment in, the device particularly described in the body of this specification and illustrated by the accompanying drawing, in which:—

Figure 1 is an elevational view of a flag staff and a device for detachably mounting the same vertically on a horizontal bar;

Figure 2 is a front view thereof;

15 Figure 3 is a side view of the same;

Figure 4 is a top view of the device, the staff being sectioned on line 4—4 of Figure 2; and

20 Figure 5 is an axial sectional view of a portion of the device, illustrating a modified construction thereof.

In the drawing is shown a vertical staff 1 carrying a flag 2, detachably mounted on the horizontal bumper bar 3 of an automobile or the like, by means of my device.

25 This device is made of a continuous spring wire bent to form a helical middle portion 4 adapted to receive and tightly hold the lower end of the staff, and vertical side portions 5, 5 on the opposite sides of the middle portion, spaced therefrom and approximately parallel therewith, these side portions being connected by a bottom bight portion 6 comprising an approximately horizontal middle part 7 and parts 8 at the opposite ends of part 7, this bight portion 6 extending rearwardly toward the middle portion 4 (as particularly well seen in Figure 3) so as to engage the under edge 9 of the bumper bar 3 as shown in Figure 1. Preferably the bight's parts 8 thus extend inclinedly rearwardly-downwardly so as to to wedgingly engage said edge.

30 The side portions 5, 5 extend at 10, 10 over the upper edge 11 of the bumper bar as seen in Figure 1. The helical middle portion 4 springs toward the plane in which lie the side portions 5, 5 so that the bumper bar is yieldingly held by the device, whose middle portion 4 presses on the bar's rear side and its side portions 5, 5 press on the bar's front side.

35 A screw 12 is desirably provided for holding the staff in the helical portion 4, being threaded in the lower end of the staff and its head engaging the lower end of said helical portion. As shown in Figure 5, the lower three or four coils 13 of the helical portion 4 of the device are of less diameter of the helix than are the upper coils, so

that the lower end of the staff may be screwed into said lower coils, such screwing process forming a shallow screw thread 14 in the staff's lower end. In this Figure 5, the screw's head 15 extends over the entire lower end of the helical portion.

5 I claim:

1. A device for detachably mounting a staff in vertical position on a horizontal bar support, made of spring wire and comprising a helical middle portion adapted to receive and hold the staff, a pair of side portions parallel with, and spaced from, the middle portion and at its opposite sides respectively, a bottom bight portion connecting the side portions and spaced below the lower end of the middle portion, a horizontal portion extending between and connecting the upper end of the middle portion and the upper end of one of the side portions, and a horizontal portion extending from the upper end of the other side portion toward the upper end of the middle portion, both of said horizontal portions being adapted to rest on the upper edge of said bar support, the bight portion being adapted to engage said bar support's under edge, the bar support being pressed between the middle portion on one side of the bar support and the side portions on the other side of the bar support in the mounted position of the device on the bar support.

2. A device for detachably mounting a staff in vertical position on a horizontal bar support, made of spring wire and comprising a helical middle portion adapted to receive and hold the staff, a pair of side portions parallel with, and spaced from, the middle portion and at its opposite sides respectively, a bottom bight portion connecting the side portions and spaced below the lower end of the middle portion, a horizontal portion extending between and connecting the upper end of the middle portion and the upper end of one of the side portions, and a horizontal portion extending from the upper end of the other side portion toward the upper end of the middle portion, both of said horizontal portions being adapted to rest on the upper edge of said bar support, the bight portion being adapted to engage said bar support's under edge, the bar support being pressed between the middle portion on one side of the bar support and the side portions on the other side of the bar support, the bottom bight portion being downwardly-outwardly inclined to press the bar support between the bottom bight portion on the under edge of the bar support and the said two horizontal por-

tions on the upper edge of the bar support in the mounted position of the device on the bar support.

3. A device for detachably mounting a staff in vertical position on a horizontal bar support, made of spring wire and comprising a helical middle portion adapted to receive and hold the staff, a pair of side portions parallel with, and spaced from, the middle portion and at its opposite sides respectively, a bottom bight portion connecting the side portions and spaced below the lower end of the middle portion, a horizontal portion extending between and connecting the upper end of the middle portion and the upper end of one of the side portions, and a horizontal portion extending from the upper end of the other

side portion toward the upper end of the middle portion, both of said horizontal portions being adapted to rest on the upper edge of said bar support, the bight portion being adapted to engage said bar support's under edge, the bar support being pressed between the middle portion on one side of the bar support and the side portions on the other side of the bar support in the mounted position of the device on the bar support, the lower part of the helical middle portion being of less diameter than the upper part of said helical portion so that the staff's lower end may be freely slid into said upper part and then screwed into said lower part to securely hold the staff. 5 10 15
